UNITED STATES PATENT OFFICE.

DANVILL W. STARRETT, OF SAN FRANCISCO, CALIFORNIA.

TURBINE.

No. 806,934.

Specification of Letters Patent.

Patented Dec. 12, 1905.

Application filed April 11, 1905. Serial No. 254,920.

To all whom it may concern:

Be it known that I, DANVILL W. STARRETT, a citizen of the United States, residing at San Francisco, in the county of San Francisco and 5 State of California, have invented certain new and useful Improvements in Turbines, of which the following is a specification.

This invention relates to turbines adapted to be driven by steam or other pressure fluids, 10 the object of the invention being to provide a turbine in which the steam can be utilized by expansion to its full extent and which will be economical in construction and in the prevention of leakage of the steam.

15 In the accompanying drawings, Figure 1 is a longitudinal section of the turbine, taken on the line A A of Fig. 2. Fig. 2 is a cross-section of the turbine, taken on the line B B of Fig. 1. Fig. 3 is an enlarged detail cross-sectional view showing the direction of the steam in passing between the revolving stationary buckets. Fig. 4 is an enlarged detail longitudinally-sectional view of one chamber and the runner therein.

20 Referring to the drawings, 1 represents the shaft of the turbine rotating in bearings 2, (only one here shown.) Upon this shaft are secured a series of runner-wheels 3 4 5, three being here shown, although the principle of 25 my invention may be applied equally well to a greater or less number than three of these runner-wheels. Each wheel is formed with transverse cavities or buckets 6 at the circumference and with radial cavities or buckets 7 at the sides, which latter extend outward only from plane or smooth portions 8 of said side, which plane portions 8 of said sides fit snugly against similar plane portions 9 of the casing.

30 The casing is made in two halves 10, which are fitted to each other on a vertical plane through the shaft of the turbine and are provided with flanges 11, by means of which they can be bolted together, as shown at 12. Said 35 casing-sections, in addition to the end walls 13 thereof, are provided with partitions 14, which extend snugly around the shaft of the turbine to prevent leakage, and said partitions, in like manner as the ends of the casing, 40 have the smooth or plane portions 9 fitting against the plane portions 8 of the runner-wheels to prevent leakage of the steam. Said partitions thus form chambers 15 for the runner-wheels. The casing-sections have the 45 internal transverse cavities or buckets 15 in the circumference of the chambers at the sides

of the end walls and partitions corresponding in form and number with the transverse cavities or buckets 6 in the circumferences of the runner-wheels and the radial cavities or buckets 17 corresponding in form and number with the radial buckets 7 on the runner-wheels. The wheels and chambers of the casing are of such relative size that the edges of the cavities in the wheels just clear the edges of the 60 cavities in the casing. These cavities are preferably made of a curvature symmetrical in both directions—forward and backward—as this form is believed to give the best results.

70 The steam or other pressure fluid enters the first chamber 18 of the casing at the bottom by the inlet-pipe 19 in a vertical tangential direction. The steam impinging upon the buckets of the runner-wheel with great velocity impels it forward in the direction of the steam, and in passing between the buckets of the runner-wheel and those of the casing, either the radial buckets at the sides or the transverse buckets at the circumference, 75 is deflected from a bucket on the wheel against a bucket on the casing, causing it to strike another bucket upon the wheel, again impelling it forward, being thus deflected a number of times in succession until it has passed nearly through a complete circumference of the first runner-wheel, when it flows by a curved pipe 20 to the entrance 21 of the second chamber 22 of the casing. This chamber 22 and the runner-wheel therein are larger 80 than the first chamber and runner-wheel to allow for the expansion of the steam. Around this runner-wheel and chamber the steam travels as before, continually expanding and imparting its velocity to the second runner-wheel, then emerging from the chamber 22 by a curved pipe 23, which leads to the upwardly-extending inlet-opening of the third chamber 24, which is still larger than the second chamber, as is also the runner-wheel 85 therein. Around this runner-wheel and chamber the steam travels, continually expanding and emerging by the downwardly-directed exhaust-pipe 25.

90 It will be seen that this construction allows full opportunity for the expansion of the steam. Whether the steam passes over the circumference or the sides of the runner-wheel it is in all cases deflected by the buckets on the casing into such a direction as to 95 impinge upon the buckets of the runner-wheel to repeatedly impart its velocity there-

to. Moreover, it cannot escape except by passing continually in contact with these buckets and transmitting its speed to the runner-wheels.

5 The construction of the turbine is very cheap, as the casing can be made of cast-iron and the runner of cast-steel.

I claim--

1. A turbine comprising a shaft, a runner-wheel thereon, having a series of radial buckets in the sides, and a casing having a series of corresponding radial buckets in the sides, the edges of the buckets in the runner-wheel just clearing those of the casing, substantially as described.

2. A turbine comprising a shaft, a runner-wheel thereon having concave radial buckets in the sides and transverse buckets in the circumference, and a casing having corresponding buckets in the sides and circumference, the buckets of the runner-wheel just clearing those of the casing, substantially as described.

3. A turbine having a shaft, a runner-wheel thereon having a plane or smooth central portion on each side and radial cavities extending from said smooth portion to the circumference and a casing having similar plane or smooth portions fitting against those of the runner-wheel and having radial concavities or buckets corresponding to those of the runner-wheel, the edges of the buckets of the one just clearing those of the other, substantially as described.

4. A turbine comprising a shaft, a runner-wheel thereon having a continuous series of concavities or buckets of a curvature symmetrical in both directions, and a casing having a similar series, the edges of the buckets of one just clearing those of the other, substantially as described.

5. A turbine comprising a shaft, a runner-wheel thereon having a continuous series of radial concavities or buckets of a curvature symmetrical in both directions, and a casing having a similar series, the edges of the buckets of one just clearing those of the other, substantially as described.

6. A turbine comprising a shaft, a runner-wheel thereon having a continuous series of transverse circumferential concavities or buckets of a curvature symmetrical in both directions, and a casing having a similar series, the edges of the buckets of one just clearing those of the other, substantially as described.

7. A turbine comprising a shaft, a series of successively-increasing runner-wheels thereon and a casing having a series of partitions fitting closely around the shaft, forming chambers successively increasing in size to correspond with the runner-wheels, each runner-wheel having a series of concavities or buckets, and the casing having in each chamber corresponding series of concavities or buckets, the edges of the buckets of one just clear-

ing those of the other, a tangential supply-conduit for the pressure fluid to the smallest chamber of the series, a pipe leading from said smallest chamber and discharging tangentially into the next larger chamber of the series, and so on in succession, substantially as described.

8. A turbine comprising a shaft, a series of successively-increasing runner-wheels thereon and a casing having a series of partitions fitting closely around the shaft, forming chambers successively increasing in size to correspond with the runner-wheels, each runner-wheel having a series of radial concavities or buckets, and the casing having in each chamber corresponding series of concavities or buckets, the edges of the buckets of one just clearing those of the other, a tangential supply-conduit for the pressure fluid to the smallest chamber of the series, a pipe leading from said smallest chamber and discharging tangentially into the next larger chamber of the series, and so on in succession, substantially as described.

9. A turbine comprising a shaft, a series of successively-increasing runner-wheels thereon and a casing having a series of partitions fitting closely around the shaft, forming chambers successively increasing in size to correspond with the runner-wheels, each runner-wheel having a series of transverse circumferential concavities or buckets, and the casing having in each chamber corresponding series of concavities or buckets, the edges of the buckets of one just clearing those of the other, a tangential supply-conduit for the pressure fluid to the smallest chamber of the series, a pipe leading from said smallest chamber and discharging tangentially into the next larger chamber of the series, and so on in succession, substantially as described.

10. A turbine comprising a shaft, a series of successively-increasing runner-wheels thereon and a casing having a series of partitions fitting closely around the shaft, forming chambers successively increasing in size to correspond with the runner-wheels, each runner-wheel having a series of radial buckets and a series of transverse circumferential concavities or buckets, and the casing having in each chamber corresponding series of concavities or buckets, the edges of the buckets of one just clearing those of the other, a tangential supply-conduit for the pressure fluid to the smallest chamber of the series, a pipe leading from said smallest chamber and discharging tangentially into the next larger chamber of the series, and so on in succession, substantially as described.

In witness whereof I have hereunto set my hand in the presence of two subscribing witnesses.

DANVILL W. STARRETT.
